DESIGN FOR A FISHING REEL

James Robert Young and Howard Young,
Mayfield, Redditch, England

Application December 12, 1938, Serial No. 81,733
In Great Britain November 19, 1938

Term of patent 7 years

To all whom it may concern:

Be it known that we, James Robert Young and Howard Young, both subjects of the King of Great Britain and both residing at Mayfield Works, Mayfield, Redditch, England, have invented a new, original, and ornamental Design for a Fishing Reel, of which the following is a specification, reference being had to the accompanying drawing, forming part thereof.

Fig. 1 is a side elevational view of a fishing reel showing our new design.

Fig. 2 is a top plan view of said fishing reel.

Fig. 3 is a side elevational view of the other side of said reel.

We claim:

The ornamental design for a fishing reel, as shown.

JAMES ROBERT YOUNG.
HOWARD YOUNG.
